UNITED STATES PATENT OFFICE.

HOMER A. GLEASON, OF HAMPSHIRE, ILLINOIS.

WATER-TANK.

SPECIFICATION forming part of Letters Patent No. 377,427, dated February 7, 1888.

Application filed August 8, 1887. Serial No. 246,406. (No model.)

To all whom it may concern:

Be it known that I, HOMER A. GLEASON, a citizen of the United States, residing in Hampshire, in the county of Kane and State of Illinois, have invented a new and useful Improvement in Water-Tanks, of which the following is a specification.

This invention relates to the construction of the metallic fastenings by which the parts of wood tanks or troughs, principally used in watering farm-stock, are held together. My design therein has been to render the fastenings readily applicable and removable, to adapt them to clamp the various parts in such manner as to make all the joints water-tight, and also to so construct them that the pressure exerted by them may be quickly increased whenever and in whatever part of the tank a leak occurs.

The main feature of the invention consists in the employment of transverse straining-bands consisting of angle-irons at each of the corners of the tank, with female screws formed in each end, and connecting-bolts between each pair of angle-irons, such bolts being reversely threaded at their ends and adapted to enter the threaded ends of the angle-irons. By the use of these bands the horizontal joints in the sides and ends can be clamped very tightly, and the same is true of the joints in the bottom and of those between the bottom and sides.

Another feature of the invention consists in the clamping device employed at the ends of the tank, the same being a hook setting down upon the end plank and having a shank shaped like an inverted T and adapted to receive the tightening-bolts extending from each side and the bottom of the tank.

In the accompanying drawings, which form a part of this specification, and in which similar letters of reference indicate like parts, Figure 1 is a perspective of my improved tank. Fig. 2 is an end elevation of the same. Fig. 3 is an end elevation showing a modified construction. Fig. 4 is a detail section of the angle-irons and the tie-bolts employed therewith.

In said drawings, A represents the sides, B the ends, and C the bottom, of the tank. Each

of these may be formed of a single plank or of two or more separate planks. The tank illustrated shows both the sides and ends made in two parts, the joints between the parts being indicated at a, and in the modification, Fig. 3, they are shown in three parts with two such joints. The bottom in this latter figure is also made in two pieces, with a joint, a, as indicated.

The transverse tightening bands are composed of rigid angle-irons D, one at each corner, and the tightening-bolts E, connecting each adjacent pair of angle-irons, the bolts being reversely threaded at their ends to adapt them to enter the threaded openings d in the ends of the irons and to draw upon such irons when rotated. The central portion, e, of the bolts may be square or otherwise fashioned to receive a proper tool for turning them. These transverse bands, being continuous, are applied to each end of the tank, and in such number to the intermediate portion as the length of the tank or the strength desired may demand, and it will be observed that by the use of these bands great facility is obtained, both in putting the tanks together and also in tightening the joints wherever and whenever they may need it, the vertical bolts serving to tighten the joints between the parts composing the sides, and the bottom bolts acting to close any leaks between the parts of the tank-bottom or in the joints between the bottom and sides. At the same time the bottom and the top bolts in the end bands cause the sides to hug the ends closely, and the intermediate bands prevent any tendency to bulge by the bottom or sides. The arms of the angle-irons may have such length as is requisite to enable them to sustain the bottom and sides at points away from the edges of those parts, and some of the arms may be longer than others for this purpose.

At the ends of the tank I prefer not to rely wholly upon the strengthening-bands above described, but to employ in connection therewith the hook F, engaging at its hooked end with the upper edge of the end board, and bolts G, passing through the sides and the bottom, as shown, and entering threaded openings in the lower end of said hook. The said

lower end of the hook may be advantageously fashioned like an inverted T, the limbs *f* receiving the side bolts and the center or extremity of the hook-shank receiving the bottom bolt. Lengthened washers *h* may be applied to the exterior surfaces of the tank to receive the pressure from the heads of the bolts *G*. It will be readily seen that these bolts *G*, in connection with the hook *F*, serve to clamp to the center portion of the bottom and sides at the points where these parts are least affected by the transverse bands, and also to close any joints there may be in the ends of the tank when such ends are made in two or more parts. 15 If the size or required strength of the tank demands, I may employ two or more of the hooks *F*, as shown in Fig. 3, and may also provide them with additional lateral branches *f*, whereby I am enabled to increase the number 20 of the bolts *G*, and where two or more hooks are employed together in this manner I prefer to unite them by tie-bolts *g*, similar to the bolts *E*. The washers *h*, wherever used, are placed across the joints *a*, as shown.

I claim—

1. The water-tank provided at its ends with transverse straining-bands extending entirely around the tank, and consisting of rigid angle-irons at each corner, and tie-bolts at the top, bottom, and sides, connecting said irons and adapted to draw them together, substantially as specified. 25

2. The water-tank provided with end and intermediate transverse straining-bands, each extending entirely around the tank, and consisting of rigid angle-irons at each corner, and tie-bolts at the top, bottom, and sides, connecting said irons and adapted to draw them together, substantially as set forth. 35

3. The water-tank provided with trans- 40
verse straining-bands extending entirely around the tank, and also having at their ends hooks *F* and bolts *G*, passing through sides and bottom, substantially as specified.

HOMER A. GLEASON.
